(57) **CLAIM**

The ornamental design for a video recorder for a car, as shown and described.

DESCRIPTION

FIG. 1 is a front perspective view of a video recorder for a car showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a front perspective view thereof, shown in condition of use with a mount disclosed in broken lines to illustrate an environment.

The broken lines depict portions of the video recorder for a car in which the design is embodied that form no part of the claimed design. Additionally, the broken lines showing a mount in FIG. 8 represent environmental structure and form no part of the claimed design.
